(57) **CLAIM**

The ornamental design for a lighting fixture, as shown and described.

DESCRIPTION

FIG. 1 is a front perspective view from above of a lighting fixture according to the new design;

FIG. 2 is a rear perspective view from below thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the lighting fixture that form no part of the claimed design.

The long dash-short dash lines in the drawings represent a boundary of the claimed design and form no part of the claimed design.

1 Claim, 8 Drawing Sheets
